UNITED STATES PATENT OFFICE.

GEORGE H. MITCHELL, OF NORTH YARMOUTH, MAINE.

VEHICLE-WHEEL.

No. 621,519.

Specification of Letters Patent.

Patented May 22, 1906.

Application filed January 21, 1905. Serial No. 242,142.

To all whom it may concern:

Be it known that I, GEORGE H. MITCHELL, a citizen of the United States, residing at North Yarmouth, in the county of Cumberland and State of Maine, have invented new and useful Improvements in Vehicle-Wheels, of which the following is a specification.

My invention relates to vehicle-wheels; and its primary object is to provide a novel and highly useful device of this character which is especially adapted for use upon farm-wagons and other dray-vehicles and which comprises several sections of hard wood secured together to form a wheel, each section being cut so that the grain will run lengthwise thereto to obviate any liability of the sections shrinking and becoming loose, whereby a wheel is provided which cannot be affected by the action of the atmosphere or the elements.

A further object of the invention is to provide a device of the character stated which is equipped with a novel form of hub and to provide a sleeve adapted to surround the axle-spindle and designed to be removed and replaced when worn.

The invention consists in the construction, combination, and arrangement of parts more fully hereinafter described, claimed, and illustrated in the accompanying drawings, which disclose the preferred form of my invention, and in which—

Figure 1 is a plan view of a vehicle-wheel constructed in accordance with my invention. Fig. 2 is a central longitudinal sectional view thereof. Fig. 3 is a sectional view on the line 3-3, Fig. 2. Fig. 4 is a view similar to Fig. 3, illustrating a modified form of wheel-hub. Fig. 5 is a similar view illustrating a further modification of the wheel-hub. Fig. 6 is a detail perspective view of the preferred form of wheel-hub. Fig. 7 is a detail perspective view of one of the modified forms of wheel-hub; and Fig. 8 is a detail perspective view of one of the sections of the wheel.

Referring to the drawings by reference-numerals, 1 designates a plurality of solid segmental blocks which are adapted to be constructed from hard wood, such as white-oak, and united to provide a wheel. Each section is cut to have the grain run lengthwise thereto in order to avoid any liability of the sections shrinking longitudinally, and each of said sections has one of its ends curved, as at 2, to provide when the sections are united a cylind-

rical periphery, the inner ends of said sections being concaved to provide a central opening 3 to permit the application of a metallic wheel-hub. Each section has one of its edges provided with a groove 4 and its other edge provided with a tenon 5, the tenon of one section being adapted to be received by the groove of the next adjacent section, whereby the sections are secured together 60 against relative movement or distortion. The sections are adapted to be built around a metallic hub 6, and then a tire 7 is applied thereto in the usual form.

The hub 6 is of a greater length than the width of the wheel and is provided with vertically-arranged annular flanges 8, which are adapted to engage on either side of the sections, and with laterally-projecting and horizontally-disposed flanges 8^a, adapted to 70 form sand-bands.

Bolts 9 pass through the flanges 8 and sections 1 and have secured to their threaded projecting ends nuts 10, these bolts being adapted to prevent the lateral distortion of 75 said flanges. A removable sleeve 11 is adapted to be inserted within the hub and to receive the axle-spindle 12. This sleeve is adapted to be readily removed to be replaced when worn and unfit for further use, thereby 80 adding life to the hub 6.

The modification of the hub, as disclosed in Figs. 4 and 7 of the drawings, resides in constructing a hub of two members, each being provided with the flanges 8 and sand-bands 8^a. The sleeve 11 is also used in connection with this form of hub.

The modification of the hub, as disclosed in Fig. 5 of the drawings, resides in constructing the hub of two members, each of 90 which is provided with the flanges 8. This modification of the hub differs from the modification disclosed in Figs. 4 and 7, in that the same is devoid of upwardly and laterally projecting flanges to form the sand-bands 8^a and is made of a length sufficient to project over the nut on the spindle and the flange on the axle, whereby sand and other foreign substances are prevented from lodging between the spindle and sleeve 11. In 95 this construction I have disclosed a wheel provided with an additional sleeve 12^a, the same being adapted to be interposed between the hub and the inner ends of the sections 1 and the sleeve 11.

The sleeve 12^a is tapered in reverse direction to the tapering of the sleeve 11, so as to

permit the application of the sleeve 11, and the sleeve 12° is held against rotation and lateral displacement by any suitable means. The sleeve 11 in each of the modifications is also adapted to be held against rotation, and it is apparent that these sleeves are adapted to be held against lateral displacement, as they are mounted upon the axle-spindle between the nut which is usually secured thereto and the flange 13 of the axle.

From the foregoing description, taken in connection with the accompanying drawings, the construction and mode of operation of the invention will be understood without a further extended description.

Changes in the form, proportions, and minor details of construction may be made within the scope of the invention without de-

parting from the spirit or sacrificing any of the advantages thereof.

Having thus fully described the invention, what is claimed as new is—

A wheel comprising a plurality of segmental sections, provided with mortises and tenons for the entire length of the segments, a hub having inner and outer integral flanges, said inner flanges being spaced apart for the reception therebetween of the inner ends of the sections.

In testimony whereof I affix my signature in presence of two witnesses.

GEORGE H. MITCHELL.
